UNITED STATES PATENT OFFICE.

JAMES M. PIERCE, OF OWATONNA, MINNESOTA, ASSIGNOR TO OWATONNA MFG. CO., OF OWATONNA, MINNESOTA, A CORPORATION.

SINGLE-DISK DRILL.

SPECIFICATION forming part of Letters Patent No. 736,440, dated August 18, 1903.

Application filed May 7, 1903. Serial No. 155,985. (No model.)

To all whom it may concern:

Be it known that I, JAMES M. PIERCE, of Owatonna, in the county of Steele, State of Minnesota, have invented certain new and useful Improvements in Single-Disk Drills, of which the following is a specification.

The object of my invention is to provide a simple efficient means for changing the position of the disk with respect to the direction of draft to cultivate more or less the soil in which the drill is used.

The invention consists generally in various constructions and combinations, all as hereinafter described, and particularly pointed out in the claims.

In the accompanying drawings, forming part of this specification, Figure 1 is a plan view of a single disk, its boot, a drag-bar, and the means for connecting the boot to the drag-bar. Fig. 2 is a similar view showing the disk adjusted in a different position. Fig. 3 is a side elevation, and Figs. 4 and 5 are details of the adjustable parts.

In the drawings, 2 represents a single disk journaled on a boot 3 of the usual construction. It is customary to provide some means for changing the position of the disks with respect to the direction in which they are moving, according to the character of the soil where the drill is used. Sometimes the disk will be set nearly in line with the drag-bar, as shown in Fig. 2, and in such cases a narrow furrow will be made in the soil, and the disk will not cultivate to any extent. It frequently happens, however, that the soil is such that the user of the machine desires to cultivate it while seeding, and the disk is then set at a considerable angle to the drag-bar, as shown in Fig. 1, and as the machine is moved over the field the disks will thoroughly cultivate the soil. It is sometimes desirable to set all the disks at the same angle, and in some cases it may be desirable to set them at different angles, and I therefore provide means whereby each disk is adjustable independently of all the others, so that the angle of any one disk can be changed without regard to the position of the others, or all of them may be changed and set at the same angle, if preferred.

My improvement therefore consists in pro-

viding a curved lug 4 on the front of the boot, said lug having a series of transverse grooves 5 in its curved surface, and on the drag-bar 6 I secure a casting 7, having an end portion 8, curved substantially on the same radius as the curve of the lug 4 and provided with a transverse rib 9, that is adapted to fit the grooves 5 therein. Bolts 10 secure the casting 7 to the drag-bar, and a bolt 11, passing through a slot 12 in the end 8 and into a hole 13 in the lug 4, secures the curved parts together, but permits the adjustment of the end 8 on the surface of the lug 4. By loosening the bolt 11 and changing the position of the end 8 it is evident that the angle of the disk with respect to the drag-bar will be changed also. Fitting the rib 9 into one of the grooves 5 will adapt the disk for use in one kind of soil, and the adjustment of the rib 9 in another groove will change the angle of the disk and render it more efficient in another soil. For general use the rib will be set in the middle groove, but can be readily adjusted to fit the others whenever desired.

I claim as my invention—

1. In a single-disk drill, the combination, with a boot, of a disk mounted therein, a lug on said boot having a surface curved horizontally, a drag-bar having a similar surface to fit said lug, and means adjustably securing said lug and drag-bar together, substantially as described.

2. In a single-disk drill, the combination, with a boot, of a disk mounted thereon, a lug secured to said boot and provided with a surface curved horizontally and having a series of transverse grooves, a drag-bar provided with a curved surface to fit the surface of said lug and having a transverse rib to fit the grooves therein, and means adjustably securing said drag-bar to said lug.

3. In a single-disk drill, the combination, with a boot, of a disk mounted thereon, a curved lug formed integrally with said boot and having a series of transverse grooves in its curved surface, a drag-bar, a casting secured thereto having a curved end to fit the curved surface of said lug, a transverse rib provided on said curved end to fit the grooves of said lug, and a bolt passing through said lug and through a slot in said curved end

and adjustably securing the parts together, substantially as described.

4. The combination, with a drill-boot provided with a surface curved horizontally, of a disk mounted on said boot, and a drag-bar provided with a curved surface to fit the surface of said boot, and means adjustably securing said surfaces together.

5. In a disk-drill, the combination, with a boot and a lug projecting substantially in a horizontal direction therefrom and having a curved roughened surface, of a disk journaled in said boot, and a drag-bar having a curved surface to coincide with the surface of said lug, and means for adjustably securing said drag-bar and lug together.

6. The combination, with a drill-boot hav-

ing a surface curved horizontally, of a disk journaled in said boot, a drag-bar having a curved surface to coincide with the corresponding surface of said boot, and means securing said surfaces together.

7. The combination, with a drill-boot and a lug thereon having a surface curved horizontally, of a disk, a drag-bar having a surface to coincide with the surface of said lug, and means securing said lug and said drag-bar together.

In witness whereof I have hereunto set my hand this 20th day of April, 1903.

JAMES M. PIERCE.

In presence of—

RICHARD PAUL,
S. V. GRIFFIN.
